AIR CONDITIONING APPARATUS

Fowler Manning, Bronxville, and Robert D. Lambert, North Pelham, N. Y., assignors to American Radiator Company, New York, N. Y., a corporation of New Jersey

Application October 2, 1935, Serial No. 43,204

5 Claims. (Cl. 261—1)

This invention relates to methods of conditioning air in heated room spaces and more particularly to a method of providing proper humidity conditions in room spaces during the heating season.

As the dry bulb temperature of the outside air is relatively low during the heating season, its capacity for holding moisture is relatively small. Its absolute humidity is relatively low, and this is true even though its relative humidity might be high. When this outside air is brought into a heated room space its absolute humidity remains the same, but the relative humidity becomes much lower due to its dry bulb temperature being raised. As the outside air is the ultimate source of all of the air in the room, there is always a deficiency of moisture in the heated room spaces during the heating season.

The optimum range of relative humidity values for room spaces of houses during the heating season is generally understood to be between 30% and 70%. If no means are provided for adding moisture to the room spaces, the actual relative humidities will fall well below the 30%. This, of course, will depend upon the prevailing outside climatic conditions, the number of people occupying the room spaces and the amount of moisture supplying operations such as cooking, washing, bathing, etc., done in the house.

It is an object of the present invention to provide an improved, dependable and inexpensive method of providing a proper humidity of the air in room spaces throughout the range of prevailing outside dry bulb temperatures during the heating season, without objectionable condensation of moisture on the inside surfaces of the windows and other surfaces most readily affected by the dry bulb temperature of the outside air, and without the use of humidity responsive control instruments.

The invention consists in the series of steps forming the method more fully described hereinafter, and the novelty of which will be particularly pointed out and distinctly claimed.

In the accompanying drawings, to be taken as a part of this specification, we have illustrated two alternative forms of apparatus for performing the novel steps of our method, in which drawings:

Fig. 1 is a fragmentary vertical sectional view of a conventional dwelling house, showing apparatus installed therein which performs the several steps of our improved method;

Fig. 2 is a horizontal sectional view taken on the line 2—2 of Fig. 1, and showing a portion of

the apparatus for performing the steps of our method;

Fig. 3 is a vertical sectional view taken on the line 3—3 of Fig. 1, and also showing a portion of the apparatus;

Fig. 4 is a perspective view of an alternative form of apparatus for performing the steps of our improved method; and

Fig. 5 is a graph showing by a curve the actual humidity conditions maintained over a normal range of outdoor temperatures, in the room spaces of a conventional dwelling house where our improved method was practiced, and also showing by a curve the amount of humidity that can be maintained without deposition of moisture on the windows of that house for the same range of outdoor temperatures.

In accordance with one specific aspect of our invention, our improved method comprises supplying heat to the air in a room space to maintain the dry bulb temperature of the air contained therein within a comfortable range; withdrawing from the room space a predetermined fixed quantity per unit of time of the heated air; taking from the outside air a predetermined fixed quantity per unit of time of air at its prevailing dry bulb temperature; mixing the withdrawn air with said quantity of outside air; increasing the humidity of the mixture by an amount which is a predetermined substantially fixed part of the difference between the amount of moisture in grains per pound the mixture holds prior to having its humidity increased and the amount of moisture the mixture could hold if saturated at its wet bulb temperature, so that the humidified mixture has at all times relative humidities which vary directly as a function of the dry bulb temperature of the outside air; increasing the dry bulb temperature of the humidified mixture to a point where its admission to the room space will not result in discomfort to the occupants; and introducing the heated and humidified mixture into the room.

By performing the method steps as just outlined, the air in the room space may be always maintained at a comfortable dry bulb temperature and the air will always contain a proper, comfortable and healthful amount of moisture, which amount is automatically varied with the changing outside dry bulb temperatures so that moisture in objectionable amounts will not be deposited on the inside surface of the window panes and in no case on the ceiling and walls of the room, and this is effected without the use of humidity responsive instruments.

The steps of our improved method may be carried out by a variety of apparatus without departing from the spirit of the present invention. In the drawings, we have illustrated two forms of apparatus which we have found to operate effectively in maintaining the proper condition of the air in room spaces.

Referring first to apparatus disclosed in Figures 1 to 3, inclusive, it will be observed that we have shown such apparatus as installed in a conventional dwelling house which includes a room space 10 defined in part by an outside wall 11, an inside wall 12 and a floor 13. A window 14 is provided in the outside wall 11. Beneath the room 10 is a basement space 15 defined in part by side walls 16 and a floor 17.

In accordance with one aspect of our invention, we have provided apparatus for maintaining the dry bulb temperature of the room space within a comfortable range to the individuals occupying such space. This apparatus is shown as being a conventional oil fired boiler unit 18 having an off-take steam main 19 connected by means of a pipe 20 to a radiator 21 installed within the room space. A pipe 22 connects the return end of the radiator with a return main 23 leading to the boiler 18. We have shown a thermostat 24 mounted on the inside wall 12 and operating to control the operation of an oil burner (not shown) disposed within the lower portion of the boiler unit 18. The heating apparatus shown is well known and needs no further explanation. Other forms of heating apparatus may be used without departing from the scope of the present invention. The reference character 30 indicates an apparatus which draws in a mixture of room air and outdoor air; filters the mixture; humidifies the mixture; and increases the dry bulb temperature of the mixture above that of the room and then forces such mixture into the room at a substantially fixed volume rate.

The apparatus 30 comprises an outer casing 31 having upstanding defining walls 32 and a vertical partition wall 33 defining a U-shaped passage for the flow of mixture therethrough. The partition 33 divides the casing 31 into a down-coming leg 34 and an up-going leg 35.

Arranged above the apparatus 30 is a manifold casing 36 which may be suspended from the basement ceiling and is divided by a vertical partition 37 into an air inlet chamber 38 and an air outlet chamber 39 (see Fig. 2), which communicate, respectively, with the down-coming leg 34 and the up-going leg 35 of the apparatus 30. A flexible section 40 connects the manifold casing 36 with the apparatus 30 and the section 40 is also provided with a vertical partition 41 which is so arranged with respect to the partition 37 and the partition 33 as to provide the connection just explained between the casing 36 and the apparatus 30. The flexible section may be formed of any suitable material, such for example, as canvas which may be readily cut to suit the particular distance between the suspended manifold 36 and the apparatus 30 resting on the floor of the basement. The canvas also functions as a sound deadening means.

The inlet chamber 38 is provided with a plurality of openings 42, having externally extending flange portions 43 for connecting the respective openings with air inlet ducts 44. In the construction shown, one of the openings 42 is connected by a duct 44 with an opening 45 through one of the side walls 16 of the basement, and thereby 75 serves as a means for admitting outside air into

the inlet chamber 38. The other three inlet openings 42 are connected to the room spaces to be humidified by ducts 44 communicating with grille-covered openings 46 in the floor of the room spaces. In the drawings, we have shown only one opening 46 and a duct 44 connecting such opening with an inlet opening 42 of the inlet and mixing chamber 38. It will be appreciated that the other grille-covered openings 46 will be located at proper points in the rooms of the ground floor of the house to withdraw the heated air therefrom.

The outlet chamber 39 is also provided with a plurality of openings 50 which are respectively connected by outlet ducts 51 with grille-covered 15 openings 52 through the floor of the room spaces.

A damper 53 is disposed within each of the inlet openings 42 of the inlet chamber 38, and are operated respectively, by suitable lever arms 54 arranged on the outside of the respective flange 20 portion 43. By regulating the dampers 53, the proportions of outside air and room air drawn into the mixing inlet chamber 38 may be varied. As will later appear, the proper proportions are first determined and the dampers then remain 25 in their selected positions, without further adjustment being required.

Disposed across the upper portion of the down-coming leg 34 of the apparatus 30 are a pair of filters 55 which are suitably arranged in the form 30 of an inverted V and function to take out of the incoming air mixture substantially all of the foreign matter and dirt entrained therein.

Arranged below the filters 55 is a humidifying chamber 56 which forms a part of the down-coming leg 34 and has installed therein a plurality of spray nozzles 57 suitably connected to the city water supply by a pipe 58. In the extreme lower end of the humidifying chamber is arranged an evaporator-eliminator unit 60, against which the 40 sprays of water from the nozzles 57 play and which cooperate with the sprays to effect the humidifying of the mixture and also serve to eliminate any free moisture entrained in the humidified mixture. The evaporator-eliminator 45 60 is suitably arranged diagonally across the lower end of the down-coming leg 34 and extends entirely across the leg 34 so that all of the air mixture passes therethrough.

This eliminator 60 may be constructed in any 50 suitable fashion and of any suitable material. The eliminator shown comprises a relative shallow rectangular frame 61 having its opposite sides formed of spaced metallic screens 62, between which is disposed a suitable vaporizing and 55 moisture eliminating mat 63; such for example, as layers of spun glass, metal wool, or the like. The mat is so constructed as to provide a multitude of interstices and tortuous passages for the air flowing therethrough. The surfaces of the 60 mat are kept wet by water from the sprays, and the air in passing therethrough contacts with the exposed surfaces of the water particles on the surfaces of the mat and effects evaporation of the water and humidification of the air in a manner well known in the art. Due to the baffling effect caused by the tortuous passages, any free moisture entrained in the air mixture will be taken out and will flow downward through the mat and into a sump 64. A suitable drain 64a 70 is provided for conducting away the excess water.

The sprays may be adjusted to vary their humidifying characteristics and thereby vary the extent to which the mixture is humidified. The humidifying characteristics are temperature, 75

pressure, flow and degree of fineness of the spray; and, with the exception of temperature, these characteristics may be varied by suitable regulating screws 65 disposed on the upper end of each 5 of the nozzles, and also by varying the pressure of the water against the nozzles by regulating a suitable valve 66 in the pipe 58 connected to the city water supply line. As will later appear, when the desired values of these characteristics are 10 once determined, they remain fixed during the operation of the apparatus. The temperature of the city water will, of course, vary within a small range, but the range is so small that its effect on the operation of the method will not make 15 sufficient difference to justify its regulation.

Arranged within the lower portion of the up-going leg 35 of the apparatus 30, is a blower 67, comprising a casing 68 and a rotating element 69. The casing 68 is provided with a pair of inlet 20 openings 70 communicating with the space 71 on the down stream side of the eliminator 60, there being one opening through each side of the casing 68. The casing 68 is provided with an outlet opening 72 connecting with a diverging passage 25 73 which forms a part of the up-going leg 35 of the apparatus. The rotating element 69 is suitably driven by an electric motor 75 which is connected by a belt 76 with a pulley on the shaft of the rotating element.

Arranged across the upper end of the up-going 30 leg 35 is a radiator 78 consisting of a plurality of pipes 79 with fins 80 secured thereto for the purpose of promoting heat transfer. The radiator 78 is connected to the supply and return mains 35 19 and 23 of the boiler unit 18 by pipes 81 and 82, respectively.

The radiator 78 serves to raise the dry bulb 40 temperature of the air mixture above that of the room, so that when the mixture is introduced into the room, it will not result in discomfort to the occupants. For example, in a case where the rooms are maintained at a dry bulb temperature approximating 72° F. by or in conjunction with a suitable heating system, we have found that it 45 is desirable to temper the humidified air to a temperature ranging between 78° F. and 85° F.

It is to be understood that, while we have elected to disclose in the preferred embodiment of our method, the step of heating the room space 50 by a conventional heating method and the step of merely tempering or raising the temperature of the humidified mixture prior to entering the room, our invention in all of its aspects is not to be considered as being so limited; for, in so far as certain of the broader aspects of our method 55 are concerned, all of the heating of the humidified mixture and the air in the room may be effected either by the conventional room heating equipment or by a unit like the radiator 78 of sufficient capacity and arranged in the path of 60 the air coming from the humidifier.

The structure shown in Figs. 1, 2, and 3 and as just described operates to perform the several 65 steps of our improved method and will maintain in the room space 10 proper humidity values, without the objectionable deposition of moisture on the window panes and without any deposition of moisture on the ceilings or walls of the room space.

The temperature of the inside surfaces of the 70 windows and similarly exposed wall surfaces is a resultant of the dry bulb temperature of the air in the room and the dry bulb temperature of the outdoor air. As the room temperature re- 75 mains at a substantially uniform value, depend-

ing on the desires of the occupants, the inside surface temperature of the windows will vary directly as a function of the changing outdoor dry bulb temperature. Condensation occurs on the inside surfaces of the windows and similarly affected surfaces when the temperature of these surfaces is below the dewpoint temperature of the air in the room space. 5

The amount of moisture which air will take up in passing through a humidifier of the type shown 10 varies directly as a function of the dry bulb temperature of such air before entering the humidifier. With the blower 67 operating at a constant rate of speed and with the dampers 53 at fixed positions, fixed proportions of room air and 15 outdoor air will flow into the mixing inlet chamber 38, and this mixture will pass through the humidifying chamber 56 at a substantially uniform 20 volume rate. The dry bulb temperature of the mixture in the chamber 38 is a resultant of 25 the dry bulb temperature of its room air constituent and its outdoor air constituent, and therefore varies directly as a function of the changing outdoor dry bulb temperature. Therefore, with the humidifying characteristics of the sprays being fixed and the volume rate of air flow through the sprays and eliminator being fixed, the amount of moisture added to the mixture will vary directly as a function of the dry bulb temperature 30 of the outdoor air. We have found that moisture will be added to the mixture in amounts which are a substantially fixed part of the difference between the amount of moisture in the mixture prior to entering the humidifying chamber 56 and the amount the mixture could hold were it saturated at its wet bulb temperature. The humidifying efficiency of the sprays and eliminator is 35 the relationship between the amount added to the mixture and the amount the mixture could hold were it saturated at its wet bulb temperature. 40 The measure of the humidifying efficiency is the value of the aforementioned "part" by which the moisture content of the mixture is increased.

From the above, it is apparent that, with the 45 proportions of room and outdoor air substantially constant and the humidifying efficiency substantially constant, and with the volume rate of air passing through the apparatus 30 and into the room substantially constant, the moisture content, and consequently the dewpoint temperature 50 of the air in the room, will vary directly as a function of the changing outdoor dry bulb temperature and the inside window surface temperature. Therefore, by predetermining and fixing the proportions of room air and outdoor air, the humidification efficiency, and the volume rate of air flow 55 with respect to the humidification requirements of a particular house, the dewpoint temperature of the air in the rooms can be made to vary with the inside surface temperature of the windows 60 and never exceed a point where objectionable condensation will occur on these surfaces.

It is to be noted that, according to our method, the desired humidity condition is maintained in the room, without objectionable condensation; and that this result is continuously and automatically obtained without the necessity of further changing the proportions of outdoor and room air and the humidifying efficiency. For this reason, our method has a distinct advantage over prior art humidifying methods using instruments and control systems to regulate the proportions of room and outdoor air and/or to regulate the humidifying efficiency. Such instru- 70 75

ments and control systems are costly and are at least of questionable durability and accuracy.

Fig. 5 of the drawings, is a graph showing the actual results obtained in a conventional dwelling house in the area around New York city, wherein apparatus of the type shown in Figs. 1, 2 and 3 was installed. This house has a cubic foot capacity of approximately 25,000, and the apparatus was of a size to introduce into the room about 900 cubic feet of humidified air per minute. It will be appreciated, of course, that the capacity of the apparatus will be varied to suit the capacity and conditions of the particular house where it is installed.

15 The dotted line curve in Fig. 5 shows the humidity values that can be maintained in this house for the normal range of outside dry bulb temperatures during the heating season without condensation of moisture on the window panes. 20 We have elected to call this curve the "allowable relative humidity" curve. This curve indicates the relation just explained with normal outside wind velocities, and will vary slightly up or down on the graph between no wind condition and 25 high wind velocities, respectively.

30 In this particular house, the windows have single panes, and no storm windows are installed. With storm windows, the allowable relative humidity curve would be substantially the same 35 shape as that shown, but would be higher on the graph, as higher relative humidities could be maintained in the room spaces without condensation on the window, because of the resulting higher inside surface temperatures of the windows, the spaces between the storm windows and customary windows acting as a heat insulator from the outside dry bulb temperatures, and also acting to nullify the effect of high wind 40 velocities, which produce lower inside window surface temperatures.

45 The full line curve on the graph indicates the mean actual humidities maintained in this house during the heating season by following the steps of our improved method. The curve shows the results obtained when the proportions of outside to inside air used were set at 1 to 3 and the efficiency of the humidifying chamber was approximately 40%, that is to say, when the humidifying chamber added to the air 40% of the 50 difference between the absolute humidity of the mixture prior to entering the chamber and the absolute humidity of the mixture if saturated at its wet bulb temperature.

55 From an examination of Fig. 5, it will be observed that for temperatures below 20° above 0° F., the relative humidities maintained were 30% and slightly less, and that the curve showing the actual relative humidities maintained in the room crosses the allowable relative humidity 60 curve at 10° above 0° F. Therefore, for temperatures below 20° above 0° F., slightly less than the accepted optimum of 30% relative humidity was maintained; and for temperatures below 10° above 0° F. a slight fog or frost appeared on the 65 window panes, but not to such an extent as to cause moisture to run down the window pane and result in puddles.

70 Variations of the actual relative humidity curve were obtained by using different proportions of outside and inside air and using a different efficiency value in the humidifying chamber. It was found that as the proportion of outside air to inside air was increased the actual relative humidity curve for the room would more 75 closely approximate the allowable relative hu-

midity curve; but, in so doing, the amount of fresh air added to the rooms would, of course, increase the heating load on the house. It was also found that if the efficiency of the humidifying chamber were raised to 60% with a 1 to 3 proportion of outside and inside air, the actual relative humidity curve would be approximately the same shape as the one shown, but would cross the allowable relative humidity curve at a higher outside dry bulb temperature. Frost 10 appeared on the windows at a higher outside dry bulb temperature, but not in amounts objectionable to the occupants even at extreme low temperatures.

15 From the above, it will be readily understood that the proportion of inside and outside air and the humidifying efficiency may be selected to maintain the humidity condition desired by the occupants of a particular house, and, when once determined, such humidity condition will be 20 maintained automatically in the manner heretofore explained. The adjustments may be such that the relative humidity of the air at the house is maintained within the optimum range of 30% to 70%, and the deposition of moisture on the 25 window panes will not be objectionable at the low temperatures. We have found that in reality it is not absolutely necessary, in order to have a refreshing and healthful condition, for the relative humidity to be maintained at a minimum of 30%. Therefore, in cases where the occupants do not like to have a deposition of fog or frost on the window at the low temperatures the adjustment may be such that proper, or 30 healthful and refreshing humidity conditions 35 may be secured without the deposition of moisture in the form of frost or fog. The operation and range of results and conditions indicated on the graph in Fig. 5 are considered by us to be satisfactory. However, as just explained, in accordance with our method they may be varied to 40 suit the conditions and the particular desires of the occupants of any particular house.

45 In addition to the previously explained benefits derived from maintaining automatically proper humidity conditions in the room spaces, our improved method also keeps the air in motion in the room spaces and maintains therein an even and positive supply of clean and fresh air without objectionable drafts. The room 50 spaces are kept under a slight positive pressure, due to the fact that more air is supplied than is withdrawn, and this condition tends to prevent the entrance of dust and dirt from the outside through cracks and crevices around the windows 55 and doors in the house. The latter, in conjunction with the cleansing of all of the air supplied to the room, keeps the room spaces relatively clean. In so far as the fresh air condition of the room spaces is concerned, there is a decided advantage over methods not employing positive 60 ventilation, for in houses where the amount of fresh air supplied depends upon the infiltration of outside air through cracks around windows and doors, too much air is supplied when there 65 are high wind velocities on the outside and too little ventilation is provided when there is no wind.

70 In Fig. 4 of the drawings, we have shown an alternative form of apparatus which performs the several steps of our improved method previously explained. The apparatus is indicated by the reference numeral 100 and comprises a casing 101 suspended from the basement ceiling. At one end of the casing is provided a pair of 75

ducts 102 and 103 which are adapted to communicate respectively with the outside air and with the room spaces. The ducts 102 and 103 are provided with dampers 104 and 105 respectively, which serve to properly proportion the amounts of outside air and room air drawn into the casing 101. At the opposite end of the casing 101 is provided three air supply ducts, which are indicated by the reference character 106 and are adapted to be connected to grille-covered openings in the floor of a room space in the same manner as the ducts 51 of the previously described apparatus.

The fresh air inlet duct 102 and the recirculating air duct 103 communicate with an air inlet chamber 107 provided in the adjacent end of the casing 101, which chamber serves to mix the room air and fresh air. The side of the chamber 101 opposite to the entrance of the ducts 102 and 103 is defined by a filter 108 of any suitable construction, through which the air mixture flows from the chamber 107 and which serves to remove from the air mixture particles of dust and dirt entrained therein.

On the down stream side of the filter 108 is a humidifying chamber 110, which performs the function of adding moisture to the filtered air mixture in amounts which are a predetermined fixed part of the difference between the absolute humidity of the mixture prior to entering the chamber and the absolute humidity of the mixture if saturated at its wet bulb temperature. Humidification is effected by a plurality of water nozzles 111 arranged in the chamber 110 and supplied with water from a suitable pipe 112 connected to the city water supply. The nozzles 111 are of the type which provide a very small, high velocity stream of water which strikes a surface of a suitable breaker plate and as a result the stream is broken up into minute particles which fill the chamber 110 and are taken up by the air stream flowing through the chamber 110.

The breaker plates against which the jets of water strike are indicated by the reference character 113, there being one plate for each jet. The plates 113 are secured to the ends of arms 114 which are carried by a rotatable shaft 115 suitably journaled in the side walls of the casing 101. A lever 116 is provided for rotating the shaft and for positioning the plates 113 with respect to the jets. The humidifying characteristics and hence the humidifying efficiency of the chamber 110 may be varied by rotating the shaft 115 and thereby varying the angle at which streams of water strike the plates and the distances between the plates and the nozzles.

Disposed across the side of the humidifying chamber 110 opposite to the filter 108 is an evaporator-eliminator 120 which is constructed and functions in a manner similar to the evaporator-eliminator 60 of the previously described apparatus. The eliminator 120 performs the functions of eliminating any free moisture entrained in the air mixture flowing from the chamber 110 and of promoting evaporation of moisture and the humidification of such air mixture.

Behind the evaporator is arranged a motor blower unit 125 which comprises a motor 126 having a blower 127 arranged at each end thereof. The blowers 127 include casings 128 and rotors 129 fixed to opposite ends of the motor shaft 130. The casings 128 are provided with inlets 131 which receive the humidified air mixture flowing through the eliminator 120, and with out-

lets which are in communication with an air tempering chamber 133.

A suitable steam or hot water radiator 134 is installed in the air tempering chamber 133 and functions to raise the temperature of the air mixture to a point where its entrance into the room spaces will not be uncomfortable to the occupants. For the purpose of preventing eddying of the air flowing from the blowers and through the radiator, a splitter vane 135 is provided which divides the flow of the air as it comes from the blower and directs it to the upper and lower portions respectively, of the radiator. The opposite surfaces of the splitter vane, as well as the inside surfaces of the casing defining the tempering chamber, are lined with a sound absorbing material indicated by the reference numeral 136.

As was the case of the apparatus 30 shown in Figs. 1, 2 and 3, the apparatus 100 withdraws a predetermined fixed amount of air per unit of time from the room spaces and takes in a predetermined fixed amount of air per unit of time from the atmosphere. The air from both sources is mixed, filtered, and passed through a humidifying chamber which adds to the air moisture in amounts which are a predetermined fixed part of the difference between the absolute humidity of the mixture prior to being humidified and the absolute humidity of the mixture were it saturated at its wet bulb temperature. The temperature of the humidified mixture is then raised by passing through a radiator and the air is then forced into the room space.

What we claim and desire to secure by Letters Patent of the United States is:

1. A method of conditioning air in a room space during the heating season, without objectionable condensation on those internal room surfaces which are more readily affected by changes in outdoor dry bulb temperature, which comprises mixing substantially unvarying proportions of thermally and hygrometrically untreated outdoor air and air of substantially fixed dry bulb temperature drawn from the room space; passing such mixture at its resultant mean dry bulb temperature and at a substantially fixed volume rate through a humidifying zone having a substantially fixed humidifying efficiency; and introducing the humidified mixture into the room space, so that the dewpoint temperature of the air in the room space varies directly as a function of the changing outdoor dry bulb temperature; the substantially fixed values of the proportionate amounts of room and outdoor air, the volume rate of the air mixture, and the humidifying efficiency of the zone being so related to one another and to the humidification requirements of the room space, that the dewpoint temperature of the air in the room space does not exceed a point where objectionable condensation would occur on said internal room surfaces.

2. A method of conditioning air in a room space during the heating season, without objectionable condensation on those internal room surfaces which are more readily affected by changes in outdoor dry bulb temperature, which comprises heating the air in the room space to provide a desired comfort condition; mixing substantially unvarying proportions of thermally and hygrometrically untreated outdoor air and heated air from the room space; passing such mixture at its resultant mean dry bulb temperature and at a substantially fixed volume rate through a humidifying zone

- having a substantially fixed humidifying efficiency; and introducing the humidified mixture into the room space so that the dewpoint temperature of the air in the room space varies directly as a function of the changing outdoor dry bulb temperature; the substantially fixed values of the proportionate amounts of room and outdoor air, the volume rate of the air mixture, and the humidifying efficiency of the zone being so related to one another and to the humidification requirements of the room space, that the dewpoint temperature of the air in the room space does not exceed a point where objectionable condensation would occur on said internal surfaces.
3. A method of conditioning air in a room space during the heating season, without objectionable condensation on those internal room surfaces which are more readily affected by changes in outdoor dry bulb temperature, which comprises heating the air in the room space to provide a desired comfort condition; mixing substantially unvarying proportions of thermally and hygrometrically untreated outdoor air and heated air from the room space; passing such mixture at its resultant mean dry bulb temperature and at a substantially fixed volume rate through a humidifying zone having a substantially fixed humidifying efficiency; increasing the dry bulb temperature of the humidified mixture above that of the air in the room space; and introducing the humidified mixture into the room space so that the dewpoint temperature of the air in the room space varies directly as a function of the changing outdoor dry bulb temperature; the substantially fixed values of the proportionate amounts of room and outdoor air, the volume rate of the air mixture, and the humidifying efficiency of the zone being so related to one another and to the humidification requirements of the room space, that the dewpoint temperature of the air in the room space does not exceed a point where objectionable condensation would occur on said internal surfaces.
4. A method of conditioning air in a room space during the heating season, without objectionable condensation on those internal room surfaces which are more readily affected by changes in outdoor dry bulb temperature, which comprises heating the air in the room space to provide a desired comfort condition; mixing substantially unvarying proportions of thermally and hygrometrically untreated outdoor air and heated air from the room space; passing such mixture at

its resultant mean dry bulb temperature and at a substantially fixed volume rate through a humidifying zone having a substantially fixed humidifying efficiency; and introducing the humidified mixture into the room space so that the dewpoint temperature of the air in the room space varies directly as a function of the changing outdoor dry bulb temperature; correlating the substantially fixed values of the proportionate amounts of outdoor air and room air, the volume rate of the air mixture, the humidifying efficiency of the zone, and the humidification requirements of the room space, so that the dewpoint temperature of the air in the room space will not exceed a point where objectionable condensation will occur on said internal room surfaces; and maintaining the values established by said correlation.

5. A method of conditioning air in a room space during the heating season, without objectionable condensation on those internal room surfaces which are more readily affected by changes in outdoor dry bulb temperature, which comprises establishing and maintaining a stream of air flowing at a substantially fixed volume rate and composed of substantially fixed proportions of thermally and hygrometrically untreated outdoor air, and air of substantially fixed dry bulb temperature drawn from the room space; continually increasing the moisture content of such air stream by an amount which is equal to a substantially fixed part of the difference between the amount of moisture the air stream contains before its moisture content is increased and the amount of moisture the air stream could hold were it saturated at its wet bulb temperature; introducing the humidified stream into the room space, so that the dewpoint temperature of the air in the room space varies directly as a function of the changing outdoor dry bulb temperature; the substantially fixed values of the proportionate amounts of room and outdoor air composing the air stream, of the volume rate of the air stream, and of the part by which the moisture content of the air stream is increased, being so related to one another and to the humidification requirements of the room space, that the dewpoint temperature of the air in the room space does not exceed a point where objectionable condensation would occur on said internal room surfaces.
